(57) **CLAIM**

The ornamental design for a carrier tape, as shown and described.

DESCRIPTION

FIG. 1 is a front view of a carrier tape of a first embodiment showing our new design, with a middle portion broken away to disclose indefinite length;

FIG. 2 is a top plan view thereof, with a middle portion broken away to disclose indefinite length;

FIG. 3 is a bottom plan view thereof, with a middle portion broken away to disclose indefinite length;

FIG. 4 is a left side view thereof;

FIG. 5 is an enlarged view taken along line 5-5 of FIG. 1 thereof;

FIG. 6 is an enlarged sectional view taken along line 6-6 of FIG. 2 thereof;

FIG. 7 is an enlarged sectional view taken along line 7-7 of FIG. 2 thereof;

FIG. 8 is a front view of a carrier tape of a second embodiment showing our new design, with a middle portion broken away to disclose indefinite length;

FIG. 9 is a top plan view thereof, with a middle portion broken away to disclose indefinite length;

FIG. 10 is a bottom plan view thereof, with a middle portion broken away to disclose indefinite length;

FIG. 11 is a left side view thereof;

FIG. 12 is an enlarged view taken along line 12-12 of FIG. 8 thereof;

FIG. 13 is an enlarged sectional view taken along line 13-13 of FIG. 9 thereof;

FIG. 14 is an enlarged sectional view taken along line 14-14 of FIG. 9 thereof; and,

FIG. 15 is a referential enlarged left side view showing the transparent portion.

The claimed design is shown with a middle portion of several views being broken away to disclose indefinite length.

The broken line showing of an electronic component in FIGS. 9, 11, 14, and 15 is included for the purpose of illustrating environmental structure only and forms no part of the claimed design.
